(57) **CLAIM**

The ornamental design for a computer stand monitor arm, as shown and described.

DESCRIPTION

FIG. 1 is a top perspective view of a computer stand monitor arm in accordance with and showing my new design;

FIG. 2 is a top plan view thereof;

FIG. 3 is a bottom plan view thereof;

FIG. 4 is a front elevational view thereof;

FIG. 5 is a back elevational view thereof;

FIG. 6 is a left end elevational view thereof; and,

FIG. 7 is a right end elevational view thereof.

The broken line drawings of a computer stand, table, brackets and attachment elements in all views are for illustrative purpose only and form no part of the claimed design.
